FLUID SAMPLING APPARATUS

Noble James Roberts, Cheyenne, Wyo.

Application December 22, 1947, Serial No. 793,151

6 Claims. (Cl. 73—422)

1

This invention relates to apparatus for sampling fluids and especially to such apparatus adapted to take individual samples from any predetermined stratum of a container of the fluid to be sampled.

As an outstanding example of the utility and practical application of the invention, but not excluding the many other uses which may be made of it, the invention will be herein described in terms of its use in sampling petroleum or other liquid in large and deep tanks thereof.

An object of the invention is the provision of apparatus by the use of which a sample may be taken from any predetermined horizontal stratum of liquid in a container.

A further object is to provide a single valve structure by operation of which any stratum may be selected and a sample drawn from such stratum alone.

A further object is to provide an apparatus which will perform the functions above indicated and which may also be used for obtaining a representative or average sample of the entire contents of the container when and if desired.

A further object is to provide an apparatus which will perform all the functions above indicated and, except for making the selection of the stratum or strata to be sampled, operates by gravity alone.

A further object is to provide an apparatus of the class described and which will perform all of the above-mentioned functions but which shall be of great simplicity and economy in construction and of extreme simplicity and durability in operation.

With the foregoing and other objects in view, all of which shall more fully hereinafter appear, the invention comprises certain novel constructions, combinations and arrangements of parts as will now be described and as defined in the appended claims and as illustrated, in preferred embodiment, in the accompanying drawing in which

Figure 1 is a side elevation of my improved sampling apparatus as installed in a tank, a fragment of which is shown in section.

Figure 2 is a right end elevation of the Fig. 1 showing.

Figure 3 is a section on line 3—3 of Fig. 1.

Figure 4 is a vertical, central section of the lower portion of the Fig. 1 showing, but on an enlarged scale. It is taken on line 4—4 of Fig. 2.

Figures 5, 6 and 7 are sections, respectively, on lines 5—5, 6—6 and 7—7 of Fig. 4.

My improved sampling apparatus is adapted to be installed in any tank 10 and comprises a sup-

2

porting pipe 11, supported, in turn, in any suitable manner as by seating on the bottom of the tank, as at 11a, and having a plurality of screened apertures 11b, for permitting free movement of the fluid in the tank between the interior of the supporting pipe and the general interior of the tank so that the liquid within the supporting pipe is always at the same level as the general level in the tank. The screening of the apertures excludes the entrance into the supporting pipe of matter which might tend to clog the sampling tubes and valve, later described.

The supporting pipe is provided with a T coupling 12, from which a conduit 13 leads through the wall of the tank 11 where a tight joint is formed in any suitable manner as by collars and welding indicated at 14.

A plurality of sampling tubes 15 (eight tubes being illustrated, without limitation as to the number which may be used) are positioned within the supporting pipe and terminate therein at various predetermined heights, as desired and as illustrated at Fig. 3. The tubes are bent within the T coupling 12 and extend outside the tank through conduit 13 and are then preferably spread or flared, as seen at Fig. 4, and each tube enters an extension of itself in the form of a conduit 15a in the valve member 16 which conduits are selectively (or collectively if desired) opened by the valve later described.

The valve member is provided with an annular flange 18a adapted to be bolted, as shown, to a collar 17 which is threaded onto the outer end of conduit 13, all as clearly seen at Figs. 1 and 4.

The outward portion of the valve member forms a valve casing 18b provided with a sampling outlet 18 which is provided with a sampling valve 19. A cap or block 20 forms the outward end of the valve casing and is provided with an annular flange 20a which is bolted to flange 16c of the valve casing. The block 20 is provided with longitudinal interior grooves 20b for the purpose later described. A split frame 21, the halves of which are bolted together as at 21a, is secured to the end of block 20, in any suitable manner to form a secure, tight joint, and is centrally adapted to slidably mount the valve stem casing later described. The outer end of the frame is provided with an annular, interior bead or tongue 21b, and the hub 22a of wheel 22 has an annular groove 22b adapted to engage the tongue 21b whereby a tongue and groove connection is formed between the frame 21 and the hub 22a permitting the hub to rotate relative to the frame but preventing longitudinal movement of the hub relative to the frame.

Hollow shaft 23 is threaded through hub 22a and is longitudinally slidably mounted in block 20 and the adjacent end portion of frame 21. The shaft is provided with pins or tongues 23a adapted to slide in the grooves 20b whereby longitudinal movement of the shaft is permitted but rotation thereof prevented. Packing 24 secured by nut 24a may be provided around the shaft at the inward end of the frame.

On its outer end the shaft carries a dial plate 25 having suitable indicia thereon (here shown as numerals 1 to 8) respectively aligned with conduits 15a. Valve stem 26 is rotatably mounted in the central hollow of shaft 23 and carries wheel 27 on its outer end and the wheel carries a pointer 28. At its inner end the stem carries a valve 29 having an orifice 29a adapted to align with any one of the conduits 15a to permit passage, from the selected conduit through the orifice into the chamber behind the valve and thence through outlet and valve 18 and 19, of fluid in that stratum in the tank in which terminates that tube 15 leading into that conduit 15a which has been opened by the valve orifice. It will be understood that the valve has a fluid tight fit against the face or end of the valve chamber through which the conduits 15a are formed so that the valve closes all conduits 15a except the one opened by the orifice 29a.

The tubes 15 are coordinated with the indicia on the dial plate 25 so that each number or character on the plate indicates a tube terminating at a known height within the tank. Therefore when the operator desires a sample from any certain stratum within the tank he simply turns wheel 27 until the pointer 28 points to that character on the dial plate which indicates the tube terminating in the desired stratum and that tube will be opened and admit fluid from that stratum to the valve chamber whence it may be drawn off through valve 19. By turning wheel 27 until the pointer 28 lies midway between two characters, the valve is wholly closed and no fluid can flow through any of the conduits 15a. In this condition the valve chamber may be drained through valve 19, whereupon the chamber is ready for another sample.

If a composite, collective or average sample of all strata in the tank is desired, wheel 22 is rotated, by which rotation, because of the threaded connection between hub 22a and the shaft plus the non-rotatability of the shaft, the entire valve mechanism will be retracted and all of the conduits 15a will be opened, thus allowing fluid to flow from all strata in the tank through tubes 15 and conduits 15a into the chamber which then functions as a mixing chamber, from which the mixed or average sample may be drawn off through valve 19.

It will be understood that the tubes are preferably made of non-corrosive material and that they may be varied in diameter as desired to equalize the flow in the tubes which, otherwise, would vary due to the variations in hydrostatic pressures in the different strata.

While I have illustrated and described many details of construction, equivalent and alternative structures will occur to those skilled in the art and I am not to be limited in my protection to the details illustrated or described.

I claim:

1. In apparatus of the class described, in combination, a valve casing, a valve seat within the casing having therethrough a plurality of annularly arranged orifices, a valve head having

an orifice adapted to be aligned, selectively, with any one of said seat orifices or with none of said seat orifices, head moving means comprising a non-rotatable sleeve slidably mounted in the casing wall and carrying the head rotatably seated on its inner end, a stem affixed to the head and rotatably mounted within the sleeve, means for positively advancing and retracting the sleeve and therewith the head, said means being adapted to hold the head in either advanced or retracted position, and other means for rotating the stem and therewith the head.

2. Apparatus for sampling fluid from a plurality of areas in a container, including, in combination, a valve having a seat and a head and a casing, a plurality of conduits leading respectively from different horizontal areas within the container to said valve, there being an orifice in said seat for and communicating with each conduit, said head being rotatably mounted in the casing and thereby adapted to selectively open any one of said orifices while closing all other orifices and said head being also reciprocably mounted in said casing and adapted thereby to close all of said orifices simultaneously or to open all of said orifices simultaneously and means for rotating said head and means for reciprocating said head.

3. In apparatus as defined in claim 2, an orifice through the head, and single means for drawing from the valve casing fluid admitted thereto through the seat orifices only or fluid admitted thereto through the head orifice.

4. In apparatus as defined in claim 2, the head having an orifice and being rotatable and means for selectively rotating and reciprocating the head including a non-rotatable sleeve slidably mounted in the casing wall and adapted to reciprocate the head, a stem affixed to the head and rotatably mounted within the sleeve and adapted to rotate the head, means for longitudinally sliding the sleeve to seat and unseat the head and other means for rotating the stem and thereby the head to align selectively the head orifice with a seat orifice or with none of the seat orifices.

5. Apparatus for sampling fluid from a plurality of areas in a container, including, in combination, a plurality of vertical tubes having their upper ends terminating respectively in different horizontal areas within the container, a valve having an outlet and valve operating means outside the container, said tubes having their lower portions leading through the wall of the bottom portion of the container and terminating in the seat of said valve, there being an orifice in said valve seat communicating with each tube, said orifices being annularly arranged, and a valve head adapted to selectively open any one of said orifices while closing the other orifices whereby to permit fluid to flow through said valve head only from a selected area within the container, said valve head being reciprocable and thereby adapted to either close all of said orifices simultaneously or to open all of said orifices simultaneously.

6. Apparatus for sampling fluid from a plurality of areas in a container, including, in combination, a plurality of vertical tubes having their upper ends terminating respectively in different horizontal areas within the container, a valve having an outlet and valve operating means outside the container, said tubes having their lower portions leading through the wall of the bottom portion of the container and terminating in the

seat of said valve, there being an orifice in said valve seat communicating with each tube, said orifices being annularly arranged, and a valve head adapted to selectively open any one of said orifices while closing the other orifices whereby to permit fluid to flow through said valve head only from a selected area within the container, the tubes within the container being assembled within a vertical casing having screened openings in its walls substantially at the levels of the tops of the respective tubes whereby to exclude foreign matter while affording equal hydrostatic pressure of fluid within and without the casing at each of the various areas in which the tubes terminate.

NOBLE JAMES ROBERTS.
